STEFAN SCHVACHO, OF TRENCIANSKE TEPLICE LAZNE, CZECHOSLOVAKIA

HIGH-TENSION SWITCH FOR X-RAY APPARATUS

Application filed October 29, 1927. Serial No. 229,695.

The object of the invention is to provide a high-tension switch for X-ray radiators whereby it is possible to switch different electric currents, with one apparatus to supply 5 different lamps, as for example: X-ray lamps, quartz lamps, solus lamps, Finsen lamps and the electromagnetic lamps.

This switch is fastened on its proper porcelain insulators and has a separate chamber on 10 the manipulating table whereon the whole switch is mounted. Back of this chamber is another smaller compartment, in which sheaves are located. Due to these sheaves the switch rotates. On the front face of the distributing board a switch-handle is located and through this handle the switch is movable.

In the accompanying drawing Fig. 1 represents a front view of the apparatus looking 20 towards the switch-handle. Fig. 2 is a cross-section of the switch. Fig. 3 is a longitudinal section of the switch.

On the X-ray radiator manipulating table (1), the manipulating switching and distributing chamber (2), is located. This is 25 constructed with two compartments (7) and (8), and with the distributing board (9). These two compartments (7) and (8) are necessary because, on the distributing board (9), the low-tension wiring is located while 30 in the compartment (8), the high-tension induction current circuit is placed. Therefore, between these two chambers (7) and (8) an insulating wall (10) has been placed to prevent the high-tension induced current from 35 passing on to the front distributing board (9).

In the rear compartment (8) the high-tension switch is installed. This switch comprises four insulators, three of which, designated by numeral 3, are anchored fast to their 40 support while the fourth, designated by numeral 4 is movable. To the top insulator (3) a contact fork (11) is fastened, which is directly connected to the outgoing conductors (not shown). Into this contact fork (11), a 45 knife-switch (6) is inserted. The knife-

switch is movable from left to right. To the lower insulator (4) also a contact fork (13) is fastened. In this fork is a slot (14), through which a screw (15) passes and is fastened to the knife (6) to make the knife move 50 to the right or left as required. To the side insulators (3), contact springs (5) are fastened and these are connected to their respective circuits.

The lowest insulator (4) is firmly fastened 55 to the moving shaft (12), which turns in the bracket bearing-arm (16) and carries the turning sprocket (17) which is located in the compartment (7). A steel cable (18) is fastened to the sleeve (17) and passes over the 60 guide-sprockets (19). On the front face of the distributing board (9) is a lever-arm (20) and contact clamps (21). To the lever-arm (20) a sprocket-wheel is fastened and engages with the cable 18, so that when the lever-arm 65 is moved, it sets into motion the steel cable (18) the guiding sheaves (19) and sprocket (17).

When using and connecting the switch the following operations are required: Lever-arm 70 (20) is brought in contact with the upper contact clamps (21) on the front distributing board (9). By moving the lever-arm (20), there is set in motion the sprocket-wheel (22), through which the steel cable (18) the guide- 75 sheaves (19) and the turning sprocket (17), to which steel cable (18) is fastened with a screw not shown, also are set into motion. Sprocket (17) is keyed, firmly fastened to the shaft (12), to which the insulator (4) is made 80 fast. Then by moving the lever-arm (20) the insulator (4) will move into the required angle and will connect the knife-switch (6), to the connection on spring (5) and thus the circuit will be closed as may be seen in Fig. 2. 85

When it is desired to have the switch disconnected then the lever-arm (20) must be brought into a horizontal position and the knife-switch (6) will be in the center as seen in Fig. 3. Thus nothing will be connected. 90

I claim:

In an X-ray radiating apparatus of the character described, a chamber divided into two compartments, separated from each other by an insulating wall, and having a distributing board, forming an outer wall to one compartment, a plurality of insulators within one compartment, one being movable, and the others anchored, knife switch blades mounted on said insulators and in circuit with high tension current conductors, and means for operating the movable switch blades, located outside said compartment.

INQ. STEFAN SCHVACHO.
